(57) **CLAIM**

The ornamental design for a chair with seatback as shown and described.

DESCRIPTION

FIG. 1 is a top, left, front perspective view of a chair with seatback;

FIG. 2 is a front elevation view thereof;

FIG. 3 is a back elevation view thereof;

FIG. 4 is a left elevation view thereof, the right elevation view being a mirror image thereof;

FIG. 5 is a top elevation view thereof; and,

FIG. 6 is a bottom elevation view thereof.

The portions of the chair with seatback shown in broken lines are for illustrative purposes only and form no part of the claimed design. Dot-dash lines show the boundaries of the claimed design and form not part of the claimed design.

1 Claim, 6 Drawing Sheets
